the block 24 meets the walls of the space 14 over extended surfaces of contact. It is manifest that the pressure of the block 24 upon the column of material within the space 14 tends to be greatest at the inner margin of the annulus, and that the displacement of material under the movement of the block is greatest at the outer margin; and it will be perceived that, in consequence of the diminution in the depth of the space 14 in direction outwardly from the inner to the outer margin of the annulus, compensation is afforded, so that the force under which the paste is ejected is evenly distributed over the face of the block, and there is no such concentration of pressure at any point in the extent of the edge of the block 24 as to bring about leakage; but rather there is distribution of stress, such as to prevent the occurrence of leakage. As shown in Fig. II, the block 24 increases in circumferential extent from its radially inner edge to its outer edge. We have found that a block 24 with an angular extent of 45°-50°, as viewed in plan, adequate to insure the good effect desired. Manifestly to extend the block through a greater angular range than necessary is disadvantageous, in that it correspondingly reduces the angular extent of the space 14. Accordingly we define as a feature of our invention such a block of an angular extent of substantially 45°-50°.

The seam between the plane nether face of the cover member and the plane upper face of the bowl member is made secure against leakage, in the direction of the longitudinal extent of the column, by the extension of these meeting faces through a like interval (between the ends of the incomplete annulus) of substantially 45°-50°. Laterally of the column under pressure, the seam is guarded against leakage by the tongue-and-groove elaborations, 25, 15 and 16, 26. Beyond the tongue and groove 16, 26, toward the centre of turning, is the rabbed meeting of the edge of the cover member with the stem 12 and the applied cap 3; and beyond the tongue and groove 25, 15, at the circumference, the edges of cover and bowl are rabbed, as indicated at 27, 18.

The container and its parts may be made of suitable material—of metal, glass, vulcanite, or phenolic resin. If the bowl and cover parts be

formed of glass it will be found advantageous to interpose in the seam between them a facing of friction-enduring material—such, for example, as a sheet of vulcanite or resin. Such a facing is indicated at 6, Fig. VII.

We claim as our invention:

1. In a dispensing container for viscous material comprising a bowl member and a cover member assembled for relative rotation and including in said bowl member a space in the form of an incomplete annulus concentric with the axis on which said members are relatively rotatable, and an outlet for contained material opening from the annular space through the body of the so-assembled container; the invention described herein that comprises a block on said cover member extending into said annular space, said block increasing in circumferential extent from its radially inner edge to its outer edge, whereby as said members are relatively rotated and the block advanced in said annular space to eject contained material from said outlet leakage between the meeting surfaces of said block and said annular space is effectively inhibited.
2. A dispensing container for viscous material including a bowl member and a cover member, the space within the bowl member being shaped to the fraction of an annulus whose radius at the inner margin is substantially one third of that at the outer margin, and the cover member carrying a block in the form of a fraction of an annulus of equal size and proportions with that of the space in the bowl member and adapted in the assembly to extend within the space in the bowl member, the assembled members being relatively rotatable upon the common axis of the said annular parts, the angular extent of the cover-borne block being substantially 45°-50° as a minimum.

3. The structure of claim 1, said block being of an angular extent of from 45° to 50° as a minimum.

4. The structure of claim 1, said annular space being of diminishing depth from a point adjacent the inner margin of the annulus to a point adjacent the outer margin.
